UNITED STATES PATENT OFFICE.

JOHN S. EWERT, OF DOLTON, SOUTH DAKOTA.

HOISTING APPARATUS.

1,021,585.

Specification of Letters Patent. Patented Mar. 26, 1912.

Application filed August 29, 1911. Serial No. 646,599.

To all whom it may concern:

Be it known that I, JOHN S. EWERT, a citizen of the United States, residing at Dolton, in the county of McCook, State of 5 South Dakota, have invented certain new and useful Improvements in Hoisting Apparatus; and I do hereby declare the following to be a full, clear, and exact description of the invention, such as will enable 10 others skilled in the art to which it appertains to make and use the same.

This invention relates to an improvement in hoisting apparatus of that class especially designed for hoisting hay racks and 15 wagon boxes from a wagon bed, and depositing the same on the ground on the opposite side of the apparatus from the wagon.

The principal object of this invention is to provide an apparatus for the purpose 20 described which may be easily placed in position for use and which is capable of operation with a minimum amount of effort.

Another object of the invention is to provide an apparatus of the class described 25 which is composed of a relatively few number of parts, is therefore simple in construction, and is cheap to manufacture.

With these and other objects in view, the invention consists in the construction and 30 novel combination of parts hereinafter fully described, illustrated in the accompanying drawings, and pointed out in the claims hereto appended; it being understood that various changes in the form, proportion, 35 size and minor details of construction within the scope of the claims, may be resorted to without departing from the spirit or sacrificing any of the advantages of the invention.

40 In the drawings: Figure 1 is a side elevation of the apparatus constructed in accordance with my invention, and showing a wagon disposed in position previous to the hay rack and body being removed therefrom, Fig. 2 is a longitudinal sectional view taken through the standard, the parts attached thereto being also shown in section, Fig. 3 is a detail sectional view taken on the line 3—3 of Fig. 1, Fig. 4 is a detail 45 end view of the horizontal arm, showing the hangers and pulley depending therefrom, Fig. 5 is a detail front elevation of

the lower part of the standard showing the hoisting drum and bracket and the braces therefor. Fig. 6 is a perspective view of 55 the grappling arm, and Fig. 7 is a sectional view taken on the line 7—7 of Fig. 1.

Like reference numerals designate corresponding parts in all the figures of the 60 drawings.

Referring to the drawings, the invention comprises a standard 5 preferably formed of piping and having its lower end threaded for engagement with the threaded opening formed in an angle block 7, it being understood that the block is buried in the ground at any convenient place. Disposed within the upper end of the standard is a rotatable plug 8 having a peripheral flange 9 adapted to rest upon the adjacent end of said standard. Integral with and extending upwardly from the plug is a pair of spaced ears 10—10, said ears being formed with aligned openings wherethrough passes a pivot pin 12. The body of the plug is 70 formed on its periphery with a recess 13, said recess being disposed in a plane at right angles to the longitudinal axis of the standard, and extending around substantially one-half the circumference of the 80 plug. This recess forms consequent end walls 14—14 which constitute stops adapted for a purpose hereinafter described. Projecting through a suitable opening formed in the standard 5 is a screw 15, the inner 85 end of the screw being disposed within the recess and adapted to be engaged by one of the walls 14 thereof.

A horizontal arm 16 has one end disposed between the ears of the plug and pivotally 90 connected to the pin thereof. Disposed on opposite sides of the arm and arranged adjacent the outer end thereof are hangers 17—17, the upper ends thereof being connected by a common bolt 18 which also 95 passes through the arm. A bearing pin 19 is journaled in suitable openings in the lower ends of the hanger arms for rotatably supporting a pulley 20.

Mounted upon the standard 5 below the 100 upper end thereof is a collar 21, and this collar is adjustably mounted on by the standard means of a set screw 22. Slidably mounted above the collar 21 is a sleeve 23

having a pair of spaced ears 23^a extending from one face thereof. A bar 24 has one end disposed between the ears 23^a and pivotally connected thereto by means of a pin 25. The other end of the bar 24 is forked to form a pair of spaced ears 26—26 adapted to receive the outer end of the horizontal arm. Formed in the ears are openings which are disposed in alinement with each other, and are adapted to register with an opening formed in said horizontal arm. A bolt 29 is disposed within the alined openings.

A U-shaped eye 30 has its end portions disposed on opposite sides of the bar 24, and the extreme ends of said eye are bent around the bolt 29. One of the ends 31 is disposed between the head of the bolt and the bar 24. The other end 32 of the eye 20 is disposed between the member 24 and a nut 33 which is associated with the said bolt. It will thus be observed that by means of the head and nut the ends of the eyes are prevented from lateral spreading and consequent displacement. Also mounted upon the standard 5 is a U-shaped bracket 33^a which includes spaced legs 34—34 and a bight. Offset from the bight portion is an enlargement 36 wherein is formed an opening 37 for receiving the said standard 5. A set screw 38 is associated with the offset portion for holding the bracket in any adjusted position. Rotatably mounted between the legs of the frame is a hoisting shaft 39, 35 wherein is fixedly mounted a hoisting drum 40. One end of the shaft projects through one leg of the frame and carries a ratchet wheel 41 and a crank handle 42. Pivotally mounted upon the last mentioned leg of the 40 frame is a spring pressed pawl 43 adapted to coact with the ratchet wheel 41, and thereby lock the same against movement in one direction. Secured to the standard 5 below the hoisting drum frame and in 45 spaced relation thereto is a small sleeve 44. Brace arms 45—45 each have one end connected to the sleeve 44 at diametrically opposite points by means of pins 46. The other ends of the braces are connected to the outer 50 extremities of the legs 34 by pins 47.

The invention further comprises a hoisting cable which consists of an elongated ring 48 having a central offset portion 49, the ring opposite said offset portion being 55 straight as indicated by the reference numeral 50. Pivotally mounted on the portion 50 of the ring is a plurality of grappling arms 51. Each of these arms is formed of rod metal, and has one end bent at right 60 angles to the longitudinal axis of the ring to form a hook 52, the other end being bent around to form an eye adapted to engage the flat portion of said ring. The arms are each furthermore bent intermediate its 65 ends to form a normally inclined upper por-

tion and a vertical lower portion. These arms are arranged in pairs and the hooks of the pairs extend inwardly toward each other. A second pulley 54 is employed and depending from the axle 55 thereof is a U-shaped element 56 having a perforation formed in the bight thereof. Disposed within the said opening is a hook bolt 58, which is connected to the offset portion 49 of the ring 48. A cable 59 has one end fixedly 70 secured to the hoisting drum, and is then trained over the first mentioned pulley 20, thence around the second mentioned pulley 54, and has its free end connected to a hook 60 which is engageable with the U-shaped 75 clip 30.

In practice, a wagon is driven under the apparatus above described, and the grapple arms are connected to the hay rack 61. The hoisting drum is then actuated to elevate 80 the rack from the wagon body. After the rack has been sufficiently elevated to clear the said body, the horizontal arm is swung around to the other side of the standard. The rack can then be lowered to the ground, 85 the movement of the horizontal arm being limited by the end walls of the recess of the plug, as before described. The horizontal arm is then returned to its normal position and the grappling hooks engaged with the 90 wagon body. The wagon body can then be swung around in a manner similar to that employed with the rack, and said body can then be deposited on top of the rack. When 95 it is desired to replace the body and rack 100 the reverse operation is employed, as will be readily understood.

It will also be observed that the horizontal arm can be raised or lowered as may be desired, depending upon the height of the 105 various wagons to be unloaded.

What is claimed is:—

1. A hoisting apparatus including a standard, a plug mounted in the upper end of the standard for limited rotary movements and formed on its periphery with a recess forming consequent end walls, said recess being disposed in a plane at right angles to the longitudinal axis of the standard, a pin carried by the standard and projecting into the recess and adapted to be engaged by the end walls of said recess to limit the rotary movements of the plug, and a horizontal arm pivotally connected to the plug for vertical swinging movements. 115

2. A hoisting apparatus including a standard, a plug mounted in the upper end of the standard for limited rotary movements, a peripheral flange projecting from the plug and disposed upon the upper end of the standards, the plug below the flange being formed on its periphery with a recess forming consequent end walls, said recess being disposed in a plane at right angles to the longitudinal axis of the standard, a pin 125

carried by the standard and projecting into
said recess and adapted to be engaged by
the end walls of said recess to limit the ro-
tary movements of the plug, ears projecting
5 from the upper end of the plug, and a hori-
zontal arm pivotally connected to the ears
for vertical swinging movements.

In testimony whereof, I affix my sig-
nature, in presence of two witnesses.

JOHN S. EWERT.
